US0D1008966S

(12) **United States Design Patent** (10) Patent No.: **US D1,008,966 S**
(45) Date of Patent: ** Dec. 26, 2023

(54) **MEDICAL DEVICE CONNECTOR**

(71) Applicant: **Physio-Control, Inc.**, Redmond, WA (US)

(72) Inventors: **Christopher Alviar**, Redmond, WA (US); **Ryan Bowman**, Redmond, WA (US); **Cathlene Buchanan**, Redmond, WA (US); **Kristina Edmonson**, Redmond, WA (US); **Brendan Greetham**, Redmond, WA (US); **Jeremy Wong**, Redmond, WA (US); **Nikolaos Kalogeropoulos**, Redmond, WA (US); **Christian Schneider**, Redmond, WA (US)

(73) Assignee: **Physio-Control, Inc.**, Redmond, WA (US)

(**) Term: **15 Years**

(21) Appl. No.: **29/708,189**

(22) Filed: **Oct. 3, 2019**

(51) LOC (14) Cl. **13-03**

(52) U.S. Cl.

(57) **CLAIM**

The ornamental design for a medical device connector, as shown and described.

DESCRIPTION

FIG. 1 is a top perspective view of a medical device connector;

FIG. 2 is a right side view thereof;

FIG. 3 is a left side view thereof;

FIG. 4 is a top view thereof;

FIG. 5 is a bottom view thereof; and,

FIG. 6 is a front view thereof.

The dashed-lines represent the remainder of the article and do not form part of the claimed design, are directed to environment, and represent unclaimed subject matter.

1 Claim, 2 Drawing Sheets
